REFRIGERATOR COMPRESSOR

Leonhardt W. Benz, Mobile, Ala.

Application April 5, 1940, Serial No. 328,117

9 Claims. (Cl. 230—144)

This invention relates to a compressor or pump, and more particularly, to a compressor for use in refrigerating apparatus.

An object of the invention is to construct a compressor which is compact in form, positive in action, and has few moving parts.

Heretofore, various types of reciprocating piston, expansible chamber, and movable vane refrigerant compressors have been proposed. However, all of these types have either been cumbersome mechanisms with many parts, or possess such limited capacities as to make them uneconomical in operation, particularly for refrigerating apparatus used in connection with air conditioning systems.

The presently to be disclosed compressor or pump possesses inherent qualities which result in great displacement of fluid in proportion to the physical dimensions of the unit, and the illustrative design is such that one revolution of the driving shaft will cause two complete compression stages, each equal to approximately three-quarters of the entire displacement of the annular piston cylinder.

A further advantage of this compressor is its ease of manufacture and fabrication, and the comparatively small input of power required to drive the machine in relation to the comparatively large volume of gas compressed and consequently liquefied.

Briefly, the present invention comprises a completely housed compressor unit having identical and interchangeable right and left-hand gear trains and annular cylinder blocks in association with continuously moving pistons.

Other novel features of improvement contributing to ease and efficiency in operation will be perceived and readily understood from reading the following detailed description of a preferred embodiment of the invention in connection with the accompanying drawings, in which

Fig. 1 is a side elevation of the compressor, partly in section, and showing the power-operating means;

Fig. 2 is a vertical section taken on line 2—2 of Fig. 1, looking in the direction of the arrows;

Fig. 3 is a vertical section taken on line 3—3 of Fig. 1, looking in the direction of the arrows;

Fig. 4 is a longitudinal vertical section;

Fig. 5 is a sectional plan view taken on line 5—5 of Figs. 2 and 3;

Fig. 6 is a vertical section of a piston and part of a cylinder member taken on line 6—6 of Fig. 3;

Fig. 7 is a cross sectional view of a cylinder mounted piston taken on line 7—7 of Fig. 6;

Figs. 8, 9 and 10 are schematic showing of the right-hand gear trains at 0° or 360°, 120° and 240° positions of rotation, respectively;

Figs. 11, 12 and 13 are similar schematic showings of the left-hand gear train at 0° or 360°, 120° and 240° positions of rotation, respectively; and

Figs. 14, 15 and 16 are diagrammatic views of the positions of the pistons and valves corresponding with the 0° or 360°, 120° and 240° positions respectively of the gear trains.

Referring more specifically to the drawings, 15 numeral 1 denotes a rectangular casing or housing in which all of the compressor or pump operating mechanism is sealed. One side of the housing 1 is provided with a removable cover plate 2, whereby complete access may be had to the interior of the casing. A horizontal drive shaft 5 is mounted in the upper portion of the casing and supported in bearings 6 contained in inwardly projecting tubular extensions 7 formed integrally in opposite end walls of the housing 1. One end of the shaft 5 extends outwardly beyond the housing 1 through a conventional, flexible, shaft seal 8 retained in a tubular extension 9 having a sealed apertured end plate 10. The apertured bearing 6 supporting the 20 opposite end of the drive shaft 5 is covered and sealed by a plate 11 that is suitably bolted to the housing. The drive shaft 5 may be rotated through the medium of pulley 12, flexible belts 13, and motor 14, preferably positioned horizontally and attached directly on the top of the unit housing 1. In some instances, other flexible driving means may be found desirable, or, if preferred, direct drive means may be employed.

40 A fixed horizontal shaft 20 in the lower portion of the casing is mounted in opposed, in-turned flanges 21 which are integral with the casing, and spaced in relation to the drive shaft 5, with both shafts lying in a vertical plane. One end of the shaft 20 abuts the inner wall of

45 the housing 1, while the opposite end is formed with an integral flange plate 22 lying outside of and suitably bolted to the casing 1. A horizontal conduit or discharge passage 25 extends axially of the shaft 20 throughout slightly more than one-half of its length with a radial passage 26 connected thereto, which will hereinafter be described in detail.

50 Referring now to Figs. 1 and 4, it will be seen that the operating or fluid displacement mechanism of the unit consists of right and left-hand

gear trains, circular cylinder sections or members, and pistons, the sets of gear trains being denoted broadly as 30 and 31, respectively.

The right and left-hand cylinder sections and pistons are identical and the parts of each group are interchangeable so that the corresponding gear or other component may be used for either the right or left-hand train; and consequently, the number of different parts to be manufactured as well as the spare parts which must be stocked is kept at a minimum.

A clear understanding of the apparatus will ensue from a description of one of the sections, and in this connection, the right-hand half of the unit denoted by numeral 30 now will be taken up in detail. An upper stepped gear 35 having a large diameter 36 and a small diameter 37 is secured through integral offset hub portion 35^a and stud bolt 39^b to the drive shaft 5. The outer face of the gear 35 abuts the inner end of the inturned, tubular bearing support 7, so that when the right and left-hand gears are secured to the shaft, they completely fill the space between the side bearing holders or supports 7.

As shown in Fig. 2, the upper, double diameter gear 35 is provided with a partial series of teeth on both peripheries 36 and 37. The partial series of gear teeth do not lie in the same circular sectors, but terminate approximately on the same radial lines from the axis of their centers.

The segmental series of teeth on the diameters 36 and 37 mesh with corresponding segmental series of teeth 38 and 39, respectively, cut on the different diameter steps formed on the periphery of the right-hand half of cylindrical cylinder block 40. That is to say, the stepped gear means on the block 40 may be joined therewith in an integral manner.

The right-hand half of the cylinder block 40 is mounted on fixed shaft 20 with the smaller diameter step 38 of the block abutting a thrust bearing 41 positioned between the block and the inner edge of inturned flange 21.

In Fig. 2 of the drawings, a vertical section is shown of the right-hand driving means or train of gears which illustrates the meshing of the teeth of the upper larger diameter gear 36 with the teeth of the lower smaller diameter gear 38, together with the concomitant meshing of the upper smaller diameter gear (37) teeth with the larger diameter lower gear (39) teeth. The partial series of teeth on the several gears mesh in the manner shown in Fig. 2 when the compressor or pump is at the 0° or 360° position of its rotation, (see also Fig. 8). At this time, the left-hand train of gears is in an opposite position as diagrammatically shown in Fig. 11 of the drawings.

Each half of the cylinder block 40 is formed with a continuous, annular groove 41' in its inner abutting face so that the complete cylinder chamber is made up of the two identical halves and is circular in both outline and cross-section. An annular groove or slot 45 is provided in each half of the cylinder block 40 outwardly of the cylinder chamber, and a flexible spring ring or strip 46 is inserted therein to act as a fluid seal and prevent leakage between the relatively rotating abutting faces of the cylinder halves.

Each half of the cylinder block 40 is also provided with a laterally extending, relatively short, substantially circular piston 50 which is double-faced. These pistons 50 each have a circular shoulder or flange 51 around a minor portion of their respective peripheries for engagement with

a complementary groove 52 milled below a semi-circular socket 53 in which half of the piston fits. The pistons 50 are retained in fixed position through the medium of a countersunk bolt or screw 54 arranged to insure that the inner portion of the piston will be drawn tightly against the inner peripheral wall of the socket 53. Preferably piston rings 55 are placed around the peripheral edge of the piston to provide a gas-tight fit with the opposite half of the cylinder chamber.

Each half of the cylinder block is fitted with a spring-pressed inlet valve 60, preferably located within the cylinder chamber for the intake of gas, such as a refrigerant vapor, through respective passages 61 communicating with the interior of the casing or housing 1, as shown in Fig. 4. These inlet valves may be of any form, as, for instance, the type shown, which comprises a screw nipple 61 having an arbor 62 on the outer or cylinder chamber end thereof carrying a spring-pressed, one-way check valve 63.

The compressed gas is discharged from the cylinder chamber through either one of the two respective ports 65, which are formed in each half of cylinder block 40, as said ports pass in rotation by passage 26 communicating with bore 25 in fixed shaft 20.

The series of drawings, Figs. 8 to 16, inclusive, show the simultaneous positions of both right and left gear trains and the relative positions of their respectively associated pistons (50) and inlet and outlet means (60 and 65) when in 0°, 120°, 240° and 360° positions of rotation. Fig. 8 illustrates the meshing of the upper and lower members of the right-hand gear train at 0° or 360°, while Fig. 11 is a similar view of the left-hand train of gears at this time. Fig. 14 shows the position of the pistons (50) and valves (60) attached to the two halves of the cylinder block 40 at 0° or 360°, with the left-hand piston and valve in solid lines and the right-hand piston and valve in dotted lines. At this stage, compressed gas may be discharged through discharge means or port 65 of the dotted right-hand cylinder half, the one-way inlet valve 60 for this half being held closed by the superior pressure within the communicating portion of the cylinder. The other inlet valve 60 (which is shown in full lines) can now supply gas at casing (1) pressure to the low-pressure cylinder space between the other faces of the pistons. A comparison of the right-hand gear train of Fig. 8 with the corresponding position of the left-hand gear train of Fig. 11 shows that the former is aligned so as to commence driving its piston at greater angular speed than the drive shaft 5, and the latter to commence driving its piston at a lesser angular speed.

Therefore, when the shaft 5 has turned the large gear 36 clockwise 120° to the position of Fig. 9, the 240° rotation of meshed small gear 38 in an opposite direction will have caused the right-hand piston connected directly therewith to progress the same angular distance to the dotted line position of Fig. 15. However, the full line left-hand piston indicated in Fig. 15 will have advanced only 60° by virtue of the fact that it has been driven at its slower speed by the inverse gear ratio shown moving into mesh in Fig. 11. The differential approach movement of the two pistons, therefore, compresses the included gas to approximately one-third of its initial volume.

Next considering the relative gear positions of Figs. 9 and 12, it will be observed that the small

drive shaft gear 37 is just coming into mesh with the large cylinder gear 39, to drive the right-hand piston at reduced or slow speed, and that the left-hand piston gears (Fig. 12) have completed only half of their slow speed drive movement. From this it follows that there will be no relative motion between the pistons 50 as they move counter-clockwise from the Fig. 15 to the Fig. 16 position. But such slow motion has carried the compressed gas charge and the port 65 to the left-hand cylinder member 41 past the radial discharge passage 26 of the stationary shaft 20 to discharge said gas.

In completing the cycle of operation the respective gear trains of Figs. 10 and 13 return to the 0° or 360° condition of Figs. 8 and 11. That is to say, the final rotation of shaft 5 through 120° continues the slow speed drive of the right-hand piston for a remaining 60° and drives the left-hand piston at its fast speed for 240° of angular movement, thus restoring the pistons and valves to the initial positions of Fig. 14. This final phase of the cycle compresses a second gas charge and discharges the same when the right-hand cylinder half port 65 returns to the aligned relation with discharge passage 26, which Fig. 14 illustrates.

To summarize briefly: A cycle consists of a three-to-one compression of a first charge accompanied by the intake of a second charge, a discharge period for the first charge in which the second charge remains uncompressed, and a three-to-one compression and discharge of the second charge. Movement of the two pistons 50 is continuous, and always in the opposite direction from that of the driving shaft 5. In this manner an annular cylinder is provided which is completely swept by the two pistons, and two compressions are obtained with a single rotation of the driving element.

The compressed gas passes through a one-way discharge valve 10 at the outer end of shaft conduit or passage 25 and into a suitable outlet valve 11. From the valve 11 said gas is piped to any desired point of use, while the expanded gas or other relatively low-pressure fluid returns to the compressor unit through casing opening 13 and by way of inlet valve coupling 14.

While the invention has been described with particular reference to a certain cycle of compression and arrangement of driving gears, it will be understood that within the scope thereof other arrangements are possible which will result in a synchronous and continuous rotation of the relatively movable pistons and cylinder members with inversion of the speed ratios during the cycle. Accordingly, it is not intended that this invention be limited to the details of construction which are specifically illustrated, except as may be required by the appended claims.

Having thus described my invention, what I claim as novel and desire to secure by Letters Patent of the United States is:

1. In a rotary pump, a pair of identical relatively movable cylinder members formed and arranged completely to provide an annular cylinder chamber; a piston fixed to each movable member and operatively disposed within said cylinder chamber; means for synchronously rotating the cylinder members in the same direction at different angular speeds during one part of a revolution, at an inverse ratio of speeds still in the same direction during another part of the revolution, and at the same speed in the same

direction for the balance of the revolution; and inlet and outlet means arranged to admit fluid to the cylinder chamber and to exhaust fluid inwardly therefrom in a radial direction after it has been acted upon by the pistons.

5. In a rotary pump, a fixed shaft having a closed conduit formed therein and extending from an opening intermediate its ends through one end; a pair of relatively rotatable cylinder members formed and arranged to provide halves of a cylinder block having an annular cylinder chamber and rotatably mounted on the shaft; a cylindrical piston fixedly connected to each cylinder member and operatively disposed within said cylinder chamber; gear means for synchronously rotating the cylinder members always in the same direction and at different angular speeds during one part of a revolution, at an inverse ratio of speeds during another part of the revolution, and at the same speed for the balance of the revolution; and inlet means arranged to admit fluid to the cylinder chamber, said cylinder members each having a passage extending inwardly from the annular cylinder chamber and adapted to communicate with the conduit of the fixed shaft to exhaust fluid after it has been acted upon by the pistons.

3. A refrigerator compressor unit comprising, in combination, a pair of identical cylinder members formed and arranged completely to provide an annular cylinder chamber which is divided between said cylinder members transversely with respect to the axis of said cylinder chamber; a piston carried rigidly by each cylinder member and operatively disposed within the cylinder chamber; gear means for rotating the cylinder members and pistons synchronously and relatively in the same direction; a sealed casing enclosing the cylinder members and gear means to provide an accumulator for low pressure refrigerant vapors; a one-way check valve in each cylinder member arranged to permit entrance of vapor from the casing; and a conduit passage leading from the cylinder chamber to without the sealed casing.

4. A refrigerator compressor unit comprising, in combination, a fixed shaft having a conduit therein extending from a point intermediate its outer surface length to one end thereof; a pair of cylinder members mounted freely on said shaft formed and arranged to provide halves of a cylinder block having an annular cylinder chamber which is divided between said cylinder members transversely with respect to the axis of said cylinder chamber; a piston carried by each cylinder member and operatively disposed within the cylinder chamber; gear means for rotating the cylinder members and pistons synchronously and relatively in the same direction; a sealed casing enclosing the cylinder members and gear means to provide an accumulator for low pressure refrigerant vapors; a one-way check valve in each cylinder member arranged to permit entrance of vapor from the casing; and a conduit passage leading from the rotating cylinder chamber to the conduit of the fixed shaft and thence without the sealed casing.

5. In a rotary pump, an identical pair of relatively movable, circular cylinder members, each cylinder member having a circular groove of semi-circular cross-section oppositely disposed with respect to that of the other cylinder member to provide an annular cylinder chamber; a cylindrical piston detachably secured across the groove of each cylinder so that one half of its

effective area will extend into the opposite groove; a fixed shaft on which the cylinder members are supported for free rotation; a stepped gear integrally formed on the outer end surface of each cylinder member; a countershaft rotatably supported in spaced parallel relation to said fixed shaft; a pair of identical stepped gears secured to said countershaft for rotation therewith and arranged to drive the respective cylinder gears, each of the gears having only a partial toothed segment on each of its steps, and the toothed segments being of a size and angular arrangement to drive each cylinder member at greater and lesser speeds than the countershaft and to produce relative movement of the pistons; means for admitting fluid to the cylinder chamber; and means for exhausting fluid from the cylinder chamber.

6. In a rotary pump, a pair of relatively movable, circular cylinder members, each cylinder member having a circular groove of semi-circular cross-section oppositely disposed with respect to that of the other cylinder member to provide an annular cylinder chamber; a relatively short, double-faced, cylindrical piston detachably secured across the groove of each cylinder so that one half of its effective area will extend into the opposite groove; a fixed shaft on which the cylinder members are supported for free rotation; a stepped gear formed on the outer end surface of each cylinder member; a countershaft rotatably supported in spaced parallel relation to said fixed shaft; a pair of identical stepped gears secured to said countershaft for rotation therewith and arranged to drive the respective cylinder gears, each of the gears having only a partial toothed segment on each of its steps, and the toothed segments being of a size and angular arrangement to drive each cylinder member at greater and lesser speeds than the countershaft and to produce relative movement of the pistons; means for admitting fluid to the cylinder chamber; and means for exhausting fluid from the cylinder chamber.

7. In a rotary pump, a pair of relatively movable, circular cylinder members, each cylinder member having a circular groove of semi-circular cross-section oppositely disposed with respect to that of the other cylinder member to provide an annular cylinder chamber; a cylindrical piston detachably secured across the groove of each cylinder so that one half of its effective area will extend into the opposite groove; a fixed shaft on which the cylinder members are supported for free rotation; a stepped gear formed on the outer surface of each cylinder member; a countershaft rotatably supported in spaced parallel relation to said fixed shaft; a pair of identical stepped gears secured

to said countershaft for rotation therewith and arranged to drive the respective cylinder gears, each of the gears having only a partial toothed segment on each of its steps, and the toothed segments being of a size and angular arrangement to drive each cylinder member at greater and lesser speeds than the countershaft and to produce relative movement of the pistons; a sealed casing enclosing the cylinder members and stepped gears; and means for admitting fluid from the casing to the cylinder chamber, said fixed shaft and cylinder members being provided with means for exhausting fluid from the chamber and exteriorly of said casing.

15 8. In a rotary refrigerator compressor, a pair of relatively movable, circular cylinder members, each cylinder member having a circular groove of semi-circular cross-section oppositely disposed with respect to that of the other cylinder member to provide an annular cylinder chamber; a cylindrical piston detachably secured across the groove of each cylinder so that one half of its effective area will extend into the opposite groove; a fixed shaft on which the cylinder members are supported for free rotation; a stepped gear integrally formed on the outer surface of each cylinder member; a countershaft rotatably supported in spaced parallel relation to said fixed shaft; a pair of identical stepped gears secured to said countershaft for rotation therewith and arranged to drive the respective cylinder gears, each of the gears having only a partial toothed segment on each of its steps, and the toothed segments being of a size and angular arrangement to drive each cylinder member at greater and lesser speeds than the countershaft and to produce relative movement of the pistons; a sealed housing enclosing the cylinder members and gears; driving means for the gears carried by the housing, said countershaft having an end projecting outside the housing and connected with the driving means; means for admitting fluid to the cylinder chamber; and means for exhausting fluid from the cylinder chamber.

45 9. As a sub-combination, a circular cylinder member having an annular groove of semi-circular cross-section coaxially arranged on an end face thereof, and a relatively small groove extending transversely of the annular groove; a cylindrical piston of substantially the same diameter as the annular groove and provided with a peripheral flange complementary to said small groove, the said flange and small groove being interengaged to prevent rotation of the piston; a piston ring encircling the piston; and screw means for detachably securing the piston and its ring in the positions recited.

LEONHARDT W. BENZ.
